(57) **CLAIM**

The ornamental design for dual stacked antenna with rods, as shown and described.

DESCRIPTION

FIG. 1 is a front elevation view of a dual stacked antenna with rods, showing my design.

FIG. 2 is a top view thereof.

FIG. 3 is a bottom view thereof.

FIG. 4 is a front elevation view thereof which is twice the size as in FIG. 1, and with a break in the middle; and, FIG. 5 is a left side elevation view thereof with part of the length of the mast being cut away, the right side elevation view being a mirror image thereof.
